UNITED STATES PATENT OFFICE.

LIDA WILSON, OF GLASGOW, SCOTLAND.

ELASTIC-FLUID TURBINE.

SPECIFICATION forming part of Letters Patent No. 762,368, dated June 14, 1904.

Application filed January 30, 1904. Serial No. 191,340. (No model.)

To all whom it may concern:

Be it known that I, LIDA WILSON, a citizen of the United States of America, whose present address is 55 West Regent street, Glasgow, Scotland, have invented a certain new and useful Improvement in Elastic-Fluid Turbines, of which the following is a specification.

The present invention relates to an improvement in and to turbines operated by steam or other elastic fluid, whereby concentric sets of rotatable blades may be arranged so that the engine may be reversed or may be conjoined in their rotative effect to give maximum efficiency with minimum of length. When it is desired that the turbine shall be reversible, this is effected by constructing the respective series of blades concentrically in sets surrounding each other, one concentric set to drive the turbine forward and the other concentric set to drive it backward, the nozzles and blades being arranged in each respective set at suitable angles to the desired direction of motion to effect this. At the end of each respective concentric set of blades next the exhaust the last of the series of blades of each such respective set or a disk with outlets through it should be stationary and of sufficient strength, reinforced by suitable stays, as to be capable of sustaining the thrust of valves arranged to close its outlets, and thereby prevent motive fluid from traversing endwise through the particular set of blades desired to be rendered temporarily inoperative.

It is convenient to have several separate annular concentric motive-fluid-supply chambers each having its appropriate inlets and nozzles set at suitable angles, and the blades in the several concentric sets, placed at suitable angles to each other radially in the same wheel, are conveniently separated by an annular plate or ring between the respective sets of concentric blades to strengthen them, but not to close the radial clearance-spaces between the respective fixed and moving blades (in multiple impact-turbines) of the various concentric sets, through which the liquid of condensation is thrown centrifugally to the casing and troughs from the various concentric sets of blades. The valves at the ex-

haust ends of each concentric set of blades are separately adjustable to close either concentric set desired, and thereby prevent the motive fluid from traversing from end to end through it, so that while each set of blades 55 may be full of motive fluid the motive fluid has no endwise motion through the particular concentric set of blades temporarily closed by said valves and is therefore inoperative to drive it while so closed. 60

A turbine may therefore be constructed capable of being reversed composed of sets of concentric radial blades arranged and combined one within the other in one casing and driving the same shaft, the reverse motion 65 being obtained by the opposite angles at which the blades and nozzles are respectively arranged in and for each of the concentric radial sets and by the consequently opposite impact effect of the motive fluid in each 70 set as it passes endwise through it. A similar concentric construction is adaptable for alternatively using either of the concentric sets of blades or all the sets of blades for rotation in the one direction if the nozzles and 75 the blades of each concentric set are set to similar angles as regards the direction of rotation.

The invention is illustrated in the annexed drawings, in which— 80

Figure 1 is an end elevation of the turbine with the parts broken away where hatched into sections at various planes. Fig. 2 is a side elevation in section at the center line where hatched. Fig. 3 is an elevation of the 85 exhaust end of the turbine, partly with outside cover broken away. Fig. 4 is also an elevation of the exhaust end of the turbine with modified arrangement for controlling the exhaust-valve spindles simultaneously. 90 Fig. 5 is a section on line X Y in Fig. 1. Fig. 6 is a side view, and Fig. 7 an end view, of the rotatable valve in section where hatched. Fig. 8 is a section of the trough attached to the shell in the chambers surrounding the 95 moving wheels, and Fig. 9 illustrates the trough cut out of the fixed rings between said wheels. Figs. 5, 6, 7, 8, and 9 are upon a large scale.

A designates the bed-plate, and B the ped- 100

estals for the shaft B', carrying the turbine-drum D. The drum D has attached to it a series of wheels having radial impact-blades e e', rotated within the casing formed of the 5 shell E and heads F and M. The head F has an outer annular motive-fluid chamber G, supplied by pipes G', and an inner chamber G², supplied by pipes G³. The exhaust-head M has a chamber M' with discharge-pipe H. 10 Nozzles, as shown at a in Fig. 5, extend from the chambers G and G² nearly to the first respective impact-blades, the nozzles a being set at the angle suitable to drive the turbine as desired. The blades opposite the chamber 15 G are designated e', and the blades opposite the chamber G² are designated e. The spaces e² between the blades form channels through which the motive fluid passes from one side of the blades to the other and which direct it 20 backwardly from the issuing side. The wheels are spaced apart upon the shell of the drum sufficiently to admit intermediate flat rings F', which are attached to the casing E and are formed with blades f f' adjacent to the 25 blades e e', the faces of the blades f' being opposed reversely to the faces of the blades e', so as to receive the backward current of motive fluid and discharge it again forwardly upon the blades of the succeeding wheel. 30 The nozzles a, leading from the motive-fluid-supply chambers G and G², at suitable intervals are tapered in cross-section and are 35 suitably inclined from the chambers G and G² to their outlets, so as to deliver the motive fluid in the direction of desired rotation upon the blades e and e', respectively. Spaces may be provided between the wheels and the casing to form chambers I between the adjacent flat rings F'. Clearance-spaces 40 g, Fig. 5, are formed between the said rings and wheels to permit the centrifugal escape of liquid which may be condensed between the blades, and annular troughs h are attached to the casing within the chamber I or may be cut 45 out of the said flat rings to receive the liquid which is discharged from the wheels and prevent it from falling back upon the wheels as patented to me in the United States under No. 733,105 on July 7, 1903. 50 The chambers I and the troughs therein between the flat rings F' or the troughs cut out of the said flat rings F' serve to lead the liquid to the lowest point of the casing or of the troughs, whence discharge-pipes i conduct the 55 liquid to traps j of any suitable construction. 60 Seven of the series of moving wheels and fixed rings F' are shown, for example, upon the drum in Fig. 2; but there may be many more, and the motive fluid is therefore expanded repeatedly in passing from one wheel to another through the blades of the stationary rings F'. The rings F' extend from the outer casing or shell inwardly close to but not in contact with the shell of the drum D or to 65 the hubs of the moving wheels, and thus di-

vide the interior of the casing into separate chambers, each of which is trapped separately by the construction described, so that condensed liquid is not only discharged from the bottom without permitting gas to escape, but 70 communication between the chambers I surrounding the several moving wheels is prevented. The flat rings F' thus form partitions which prevent the motive fluid in one of these chambers I from communicating with 75 the motive fluid in any of the other chambers I, and a reduction of pressure therefore takes place by the expansion of the motive fluid in passing through the blades e and e' between the fixed blades or deflectors. 80

The last of the series of wheels and rings in my reversing turbine should be a stationary one, or a special stationary disk M² is provided, having outlet passages to the exhaust-chamber M', the said outlets being controlled 85 by suitable valves L and L'.

The head M contains an exhaust-chamber M', situated beyond the said stationary disk M², into which the exhaust is delivered and is discharged therefrom by any suitable outlet, 90 as the pipe H. Fig. 5 shows several of the nozzles a having enlarged inlets from the chamber G tapering toward their outlets next the blades, the inclination of the nozzle toward the blades forming a sharp corner at one side 95 of the nozzle's outlet, and a valve-plug c is fitted in the nozzles.

The valve c illustrated is in cross-section a sector of a circle and is fitted to a sectoral groove, so as to lie flush with one side of the nozzle when full opening of the outlet of the latter is desired. The valve is so located that when its edge nearest to the blades is turned across the outlet of the nozzle, as shown in Fig. 5, it moves toward the sharp corner at 100 the opposite side of the nozzle-outlet, and thus contracts the area of the said outlet directly adjacent to the delivery-point where the motive fluid is discharged upon the blades e or e'. The nozzle-valves may also be formed 105 with throughway for the passage of the motive fluid. This construction is adopted to prevent the expansion and consequent loss of pressure in the motive fluid when throttled at a distance from the blades before it is discharged upon the first rotating wheel, and this effect is produced by employing the rotating valves and locating them directly adjacent to the outlet of the nozzle, where they may operate at the actual delivery-point of the motive fluid upon the first series of rotating blades. 110

The stems c' of the valves are of cylindrical form and are extended radially outward through the casing or shell, which is provided with stuffing-boxes for the stems to 115 pass through. Beyond the stuffing-boxes a toothed pinion J is applied to each of the stems and meshes with an annular gear K, held upon the casing by lugs K'. These pinions can be arranged to slide on the stems in and out of 120

mesh with the gear K, so as to permit such of the valves to be turned thereby as may be desired. The gear-ring K is shown fitted upon a circular seat upon the left-hand end of the shell E, upon which it may be moved to turn the pinions in the following manner: A bracket l is attached to the shell E and supports a shaft m and worm n, which meshes with a section of teeth upon the periphery of the gear-ring K.

A hand-wheel n' upon the shaft m enables the operator to turn the gear-ring K and adjust the valves e within the nozzles either singly, several at once, or all simultaneously, according to the number of valve-stem pinions actually in mesh with the gear-ring K.

The heads M and F are shown provided with lute-joints, applied to the shaft B' where it passes through the heads, composed of rings 20 and grooves p', which are supplied with water under pressure by a pipe q' and through an annular chamber q'', which water is delivered from the chamber between the rings and grooves by suitable passages, so as to lubricate the adjacent moving parts. Such a packing of luted rings and grooves may be applied between any of the moving and stationary parts—as, for instance, the inner edges of the rings F' and the adjacent surface of the drum 25 D or of the hubs of the moving wheels or between the adjacent faces of the rings and moving wheels.

The rotating blades carried by the drum D are formed between a hub and felly, permitting each wheel to be made of cast metal or of wrought metal or steel, all cast or electrically welded together into one piece and bored to fit upon the drum D and secured thereto by any sufficient means. The parts 30 are secured by a tire or clamping-band, as already patented to me in the United States under No. 733,105.

In the exhaust-chamber M' of the head M the valves L' and L, applied to the exhaust-outlets of the disk M'', are guided by studs N.

Screws p are provided engaging into tapped sockets on the valves to move each of the valves to and from the exhaust-outlet which it covers. The spindles of the screws 50 extend through stuffing-boxes upon the cover or head M and are provided with hand-wheels P. Each spindle may be furnished with a toothed pinion o, and all the pinions of each set of spindles are connected in this case by a ring-gear q, suitably supported, gearing into all the spindles operating one valve or the set of valves controlling the exhaust of one set of concentric blades. The turning of any 55 of the hand-wheels P of either set of spindles 60 then operates the ring-gear of that set and turns all the screws of the spindles of that set simultaneously, so as to move the valves of that set as desired.

Alternatively, I may arrange that the exhaust-valve spindles P, Fig. 4, shall be oper-

ated simultaneously, but in opposite directions as regards each set of spindles controlling the exhaust outlet or outlets of each of the respective sets of concentric blades. This is shown in Fig. 4, where each spindle is provided with a sprocket-wheel, and I connect up the spindles by a link-chain O'', running in and out between the spindles, so that the inner set are revolved in one direction and the outer set in the other. Thus as one set of 75 valves is opened the other set is closed, and vice versa. The turning by hand of any one of the hand-wheels P will simultaneously operate all the other spindles, or any convenient power-gear may be used to operate the 80 sprocket-chain O'' in either direction, as desired.

By either of the aforesaid methods of control of the exhaust-apertures of the respective concentric sets of rotatable blades the motive 85 fluid may be allowed to pass endwise only through that set of blades from which the exhaust-outlets are open, and if the blades, deflecting-surfaces, and the nozzles from the supply-chambers to the rotatable blades for 90 each concentric set are arranged in opposite directions to those for the other set as regards the direction of rotation the turbine may be thus reversed.

As it is usual that the power required for 95 reverse rotation is less than for direct driving, it will be convenient that the inner set of concentric blades, having less turning moment upon the shaft, are used for reversing, while the outer set are used for direct 100 rotation.

When it is desired that the several sets of concentric blades shall each be capable in a reversing turbine of exerting equal power one with another, the inner concentric sets of 105 blades should be made longer radially than the outer concentric sets of blades, so as to present sufficiently greater blade area to the impacts of the motive fluid, so as to make up for their less number and less leverage on the 110 shaft, owing to their inner concentric position, and consequently greater proximity to the shaft. The inlet-nozzles should be correspondingly proportioned.

Instead of arranging the blades e and f and their corresponding nozzles in a reverse direction to the blades e' and f' and their corresponding nozzles they may all be set in the same relative direction, and the motive fluid would then operate upon the blades e and f' (the same as upon the blades e' and f') to rotate the turbine-shaft forwardly, and thus give means for the increase or the reduction of the power of the turbine in one direction of rotation. Figs. 1 and 2 would represent 115 this construction as fully as it represents the reversible turbine, it being understood that the blades e and f and their nozzles can in constructing the turbine be set in either direction as may be required to make the tur- 125 130

bine reversible or to vary its power in one direction of rotation.

Having now described my invention, what I claim, and desire to secure by Letters Patent, 5 is—

1. The combination with an elastic-fluid turbine having concentric passages for the axial movement of the motive fluid through the turbine, and multiple sets of radial rotatable blades to drive the shaft passing through both passages, of means applied to the exhaust-exits adapted to retain the motive fluid at initial pressure and temperature in either of the concentric passages as and when desired.
- 15 2. In combination, in an elastic-fluid turbine, concentric passages for the axial movement of the motive fluid through the said passages; radial plates on a central shaft common to both passages and carrying the several concentric sets of blades arranged at respectively reverse angles relatively to the direction of rotation; a chamber with nozzles leading to the blades, arranged respectively in each concentric set at reverse angles to those in the other concentric set relatively to the direction of rotation; and screw-down valves fitted to the exhaust-exits to retain the motive fluid at initial pressure and temperature in either of the concentric passages, as and when desired.
- 25 3. In combination in an elastic-fluid turbine; concentric sets of rotatable blades to drive the shaft, the several sets being arranged at respectively reverse angles relatively to the direction of rotation; supply-chambers for the motive fluid each having its separate inlet and adapted to serve one concentric set of blades only; nozzles from each of the said supply-chambers to the blades, set respectively at reverse angles to those leading from the other supply-chambers relatively to the direction of rotation; control-valves in such nozzles; and means to prevent the exhaust fluid from passing out of either set of concentric blades, as and when desired.
- 35 4. In combination, in an elastic-fluid turbine, concentric sets of rotatable blades to drive the shaft; supply-chambers and nozzles therefrom to convey the motive fluid to the various concentric sets of blades; an exhaust-chamber having distinct apertures from each set of concentric blades for entry thereto of the exhaust; and valves adapted to such apertures to prevent the exhaust fluid from passing out of either set of concentric blades, as and when desired.
- 45 5. In combination in an elastic-fluid turbine, concentric sets of rotatable blades to drive the shaft; supply-chambers and nozzles therefrom to convey the motive fluid to the various concentric sets of blades; an exhaust-chamber having distinct apertures from each set of concentric blades for entry thereto of the exhaust; and valves adapted to such apertures to prevent the exhaust fluid from passing out of either set of concentric blades, as and when desired.

5. In combination in an elastic-fluid turbine, concentric sets of rotatable blades to drive the shaft; supply-chambers and nozzles therefrom

to convey the motive fluid to the various concentric sets of blades; an exhaust-chamber 60 having distinct apertures from each set of concentric blades for entry thereto of the exhaust; valves adapted to such apertures; and means for connecting the spindles of each concentrically-arranged set of valves so that each 65 such set of valves may be operated simultaneously.

6. In combination in an elastic-fluid turbine, concentric sets of rotatable blades to drive the shaft; supply-chambers and nozzles therefrom 70 to convey the motive fluid to the various concentric sets of blades; an exhaust-chamber having distinct apertures thereto from each set of concentric blades; valves adapted to such apertures; and means for connecting all the spindles of all the sets of concentrically-arranged valves, so that all the valves in all the sets may 75 be operated simultaneously, but in reverse directions.

7. In combination in an elastic-fluid turbine, 80 concentric sets of rotatable blades to drive the shaft; supply-chambers and nozzles therefrom to convey the motive fluid to the various concentric sets of blades; an exhaust-chamber 85 having distinct apertures thereto from each set of concentric blades; valves adapted to such apertures; sprocket-wheels on the valve-spindles; and an endless link chain threaded about the valve-spindles of each set of concentric valves alternately, and engaging with the 90 sprocket-wheels on the valve-spindles.

8. In combination in an elastic-fluid turbine, concentric passages for the axial movement of the motive fluid through the turbine; multiple sets of rotatable radial blades to drive the shaft, 95 passing through both of the said passages; reversed troughs arranged peripherally in the compartments surrounding the rotatable blades; and exit-pipes from said compartments leading to steam-traps to remove the 100 condensed liquid from the inside of the turbine as and when formed.

9. The combination with an elastic-fluid turbine having diverse passages or chambers for the reversal of the driven shaft by the passage of the motive fluid therethrough, of valves applied to the exhaust-exits of each of such passages, adapted to retain therein the motive fluid at initial pressure and temperature, as 105 and when desired.

In witness whereof I have hereunto set my hand in presence of two witnesses.

LIDA WILSON.
